WINDOW RUNWAY OR CHANNEL

James S. Reid, Shaker Heights, Ohio, assignor to
The Reid Products Company, Cleveland, Ohio,
a corporation of Ohio

Application April 19, 1933, Serial No. 666,862

10 Claims. (Cl. 296—44.5)

This invention relates to improvements in window runways or window channel and more particularly, in runways or channel especially adapted for use with windows having their upper front corner portions cut away or removed, such as the front windows of many present day automobiles. The windshields of such automobiles are rearwardly inclined and by cutting away the upper front corner portions of the front windows of such automobiles, the front edges of the top portions of such windows can be given a rearward inclination corresponding to that of said windshields, with consequent improvement in the appearance of said windows.

To properly guide and support the vertically movable rear edge portions of such windows and the vertically movable front edge portions of the bottom parts of said windows, standard form window channel, having window-engaging side walls of uniform and regular depth, is satisfactory, but to properly guide and support the inclined front edge portions of the top parts of such windows, which edge portions move at an angle to the vertical, special window channel is necessary, namely, channel having side walls which not only are of greater depth than the side walls of standard form channel but which also are of varying depth, all as will be readily understood and as will hereinafter more fully appear.

The general object, therefore, of the present invention is the provision of standard form window channel which is suitable, without modification thereof or additions thereto, for properly guiding and supporting the vertically movable edge portions of such windows, and the provision of suitable supplemental side wall members for supplying certain portions or sections of said standard form channel with such additions thereto as to make such portions or sections suitable for properly guiding and supporting the inclined front edge portions of the top parts of such windows.

A more specific object of the present invention is the provision of standard form window channel and supplemental side wall members for certain portions or sections thereof, which channel and which supplemental side wall members are of simple and inexpensive construction, neat and pleasing in appearance, strong, durable and efficient in use, and of such character that securing of said supplemental side wall members to the side walls of certain portions or sections of said standard form channel can be easily, quickly, neatly and conveniently effected.

Further objects of the present invention are in part obvious and in part will appear more in detail hereinafter.

The present invention will be readily understood from the following description of one embodiment thereof, reference being had to the accompanying drawing in which

Fig. 1 is a side elevation of a portion of the body of a present day automobile, said body having installed in the door thereof standard form window channel with a portion or section thereof provided with supplemental side wall members to enable said portion or section to properly guide and support the inclined front edge portion of the top part of the vertically movable window with which said door is provided; Fig. 2 is a side elevation of such standard form window channel with a portion or section thereof modified by having supplemental side wall members secured thereto; Fig. 3 is a longitudinal sectional view of said channel, including the modified portion thereof, the view being taken on the line 3—3, Fig. 4; and Figs. 4 and 5 are cross sectional views of such channel, the views being taken on the lines 4—4 and 5—5, Fig. 2, respectively.

The portion 1 of the automobile body shown in Fig. 1 includes a suitable door 2 provided in its upper portion with a suitable window opening 3 adapted to be opened and closed by a suitable sashless glass window 5 mounted in said door for vertical sliding movement. The windshield (not shown) of said automobile is rearwardly inclined and in order to give the front edge portion 7 of the top part of said window a corresponding rearward inclination, the upper front corner portion 9 of said window is cut-away or removed, so that the top part of said window, from the point marked X (Fig. 1) to the top edge 8 thereof, is of gradually decreasing width.

To properly guide and support the vertically movable rear edge portion 10 of said window and the vertically movable front edge portion 12 of the bottom part of said window, standard form window channel, having side walls of uniform and regular depth, is satisfactory, such as the channel disclosed in my copending application, Ser. No. 594,040, filed February 19, 1932, to which application reference may be had, if desired.

So far as description is here necessary, said standard form channel includes, as best shown in Figs. 4 and 5, a generally channel-shaped, resilient sheet metal member having a base 15 and a pair of generally parallel side walls 16 terminating at their outer longitudinal edge portions in longitudinally disposed beads 17 which in turn termi-

nate in inwardly extending, laterally converging window-engaging flanges 18. Preferably and as shown, all parts of said channel-shaped member, except the beads 17 thereof, are enclosed in a 5 suitable covering 20, of vulcanized rubber or the like, and in order to further cushion the window 5 which this channel shaped member is adapted to receive, the rubber covered inner surface of the base 15 thereof is provided with a suitable longitudinally disposed cushioning pad 21, of felt or the like, and the window-engaging surfaces of the two rubber covered flanges 18 of said member are provided with longitudinally disposed cushioning pads 22, which also are of felt or the 10 like.

15 To guide and support the vertically movable rear edge portion 10 of window 5, a strip 25 of such standard form window channel is suitably installed or mounted in the door 2 along the rear edge portion thereof, and to guide and support the front edge portion of said window, a strip 30 of such standard form channel is suitably installed or mounted in said door along the front edge portion thereof, all as clearly shown in Fig. 1.

20 Said rear channel strip 25, without modification thereof or additions thereto, is quite suitable for guiding and supporting the vertically movable rear edge portion 10 of window 5, and the lower section of said front channel strip 30, without 25 modification thereof or additions thereto, is quite suitable for guiding and supporting the vertically movable front edge portion 12 of the bottom part of said window. However, due to the inclination of the front edge portion 7 of the top

30 part of said window, the upper section of said front channel strip 30 is not suitable, without additions thereto, for properly guiding and supporting said inclined front edge portion 7. Therefore, to make said strip upper section suitable 35 for such purpose, suitable supplemental side wall members are provided for the side walls 16 thereof, the supplemental side wall members here shown being simple sheet metal members 35 having their inner longitudinal edge portions 36 40 spot-welded at 37 or otherwise suitably secured to the outer surfaces of the uncovered longitudinally disposed beads 17 of said side walls 16.

45 Inasmuch as the top part of window 5 is of gradually decreasing width, from the point marked X (Fig. 1) to the top edge 8 thereof, the two supplemental side wall members 35 for at least a part of their length are of gradually increasing depth. In order to avoid the necessity of having said supplemental side wall members 50 of increasing depth throughout their entire length (and such avoidance is desirable for visibility and appearance purposes, etc.), the top portion of the upper section of the front channel strip 30, in the embodiment of the invention here illustrated, is bent slightly rearwardly, as at 40. As a 55 result, the depth of those parts of the supplemental side wall members 35 lying above said bend does not increase but remains constant, and yet the outer longitudinal edge portions of said supplemental side wall parts continue in alignment with the outer longitudinal edge portions of the supplemental side wall parts lying below said bend, all as clearly shown in Figs. 2 and 3 and as will be readily understood. Preferably and 60 as shown, the outer longitudinal edge portions of said supplemental side wall members 35, which edge portions have an inclination corresponding to that of the front edge portion 7 of the top part of the window 5 and extend along the front edge portion of the door opening 3, are provided 65

70 with longitudinally disposed beads 42, which beads may, if desired, be chromium-plated or otherwise suitably ornamented.

75 If desired and as shown, the supplemental side wall members 35 may be provided at their lower ends with suitable extensions 45 adapted for 80 securement to the lower section of the channel strip 30. By securing said extensions to said channel strip section first, the subsequent securement of said supplemental side wall members to the channel strip upper section can be more easily 85 and conveniently effected.

90 In the embodiment of the invention here shown, said extensions 45 are integral parts of said supplemental side wall members and comprise side wall portions 46 provided at their outer longitudinal edge portions with longitudinally disposed beads 47, which beads are continuations of the beads 42 of said supplemental side wall members. As best shown in Fig. 5, the side wall portions 46, comprising said extensions, lie alongside the outer surfaces of the side walls 16 of the lower section of the channel strip 30, being of slightly less depth than that of said channel strip side walls, and the longitudinally disposed 95 beads 47 of said extensions overlie and grip the longitudinally disposed side wall beads 17 of said channel strip section, thereby enabling the securement of said extensions to said channel strip section to be easily, neatly and simply effected. 100

105 Further features of the present invention will be apparent to those skilled in the art to which the invention relates.

What I claim is:

110 1. A window runway or channel, comprising a generally channel shaped window-receiving structure having a base and a pair of side walls terminating at their outer longitudinal edges in longitudinally disposed beads, and a pair of supplemental side wall members for said structure, 115 there being one secured to the bead of each of the side walls thereof, said supplemental side wall members terminating at their outer longitudinal edges in longitudinally disposed beads.

120 2. A window runway or channel, comprising a generally channel shaped window-receiving structure having a base and a pair of side walls, and a pair of supplemental side wall members for said structure, there being one secured to each of the side walls thereof, each of said supplemental side wall members being of varying depth. 125

130 3. A window runway or channel, comprising a generally channel shaped window-receiving structure having a base and a pair of side walls, and a pair of supplemental side wall members for said structure, there being one secured to each of the side walls thereof, each of said supplemental side wall members being of substantially uniform depth for a portion of its length and of varying depth for another portion of its 135 length.

140 4. A window runway or channel, comprising a generally channel shaped window-receiving structure having a covered base and a pair of covered side walls provided at their outer longitudinal edges with longitudinally disposed uncovered portions, and a pair of supplemental side wall members for said structure, there being one secured to the uncovered portion of each of the side walls thereof. 145

150 5. A window runway or channel, comprising a generally channel shaped window-receiving structure having a base and a pair of side walls, said structure intermediate its ends being longitudinally bent so that part of the base of said struc-

- ture extends at an angle to the remaining part of the base thereof, and a pair of supplemental side wall members for said structure, there being one for each of the side walls thereof, said supplemental side wall members having their inner longitudinal edge portions secured to the outer longitudinal edge portions of said side walls, those parts of said supplemental side wall members on one side of said bend having side wall portions of substantially uniform depth and those parts of said supplemental side wall members on the other side of said bend having side wall portions of varying depth. 80
6. A window runway or channel, comprising a generally channel shaped window-receiving structure having a base and a pair of side walls, said structure intermediate its ends being longitudinally bent so that part of the base of said structure extends at an angle to the remaining part of the base thereof, and a pair of supplemental side wall members for said structure, there being one for each of the side walls thereof, said supplemental side wall members having their inner longitudinal edge portions secured to the outer longitudinal edge portions of said side walls, those parts of said supplemental side wall members on one side of said bend having side wall portions of substantially uniform depth and those parts of said supplemental side wall members on the other side of said bend having side wall portions of varying depth, the outer longitudinal edge portions of the side wall portions of each supplemental side wall member on both sides of said bend being in alignment. 90
7. A window runway or channel for guiding and supporting the edge portion of a slidable window, said edge portion having one section thereof movable in a path inclined to the path of movement of another section thereof, said runway or channel comprising a generally channel-shaped structure having a base and a pair of side walls, said structure having one section thereof adapted to receive one section of the edge portion of said window, and a pair of supplemental side wall members for another section of said structure, there being one supplemental side wall member secured to each of the side walls of said second mentioned section of said structure, said supplemental side wall members being adapted to receive and guide the other section of the edge portion of said window. 95
8. A window runway or channel for guiding and supporting a side edge portion of a vertically slidable window, said edge portion having one section thereof movable in a vertical path and having another section thereof movable in a path inclined to the vertical, said runway or channel comprising a generally channel-shaped structure having a base and a pair of side walls, said structure having one section thereof adapted to receive the vertically movable section of the edge portion of said window, and a pair of supplemental side wall members for another section of said structure, there being one supplemental side wall member secured to each of the side walls of said second mentioned section of said structure, said supplemental side wall members being adapted to receive and guide that section of the edge portion of said window having a path of movement inclined to the vertical. 100
9. A window runway or channel for guiding and supporting a side edge portion of a vertically slidable window, the edge portion of the lower part of said window having a vertical path of movement and the edge portion of the upper part of said window having a path of movement inclined to the vertical, said runway or channel comprising a generally channel-shaped structure having a base and a pair of side walls, said structure having its lower section thereof adapted to receive the vertically movable edge portion of the lower part of said window, and a pair of supplemental side wall members of increased and varying depth for the upper section of said structure, said supplemental side wall members being secured to the side walls of said upper section and being adapted to receive and support the other movable front edge portion of the top part of said window. 105
10. A window runway or channel for guiding and supporting a side edge portion of a vertically slidable window, the edge portion of the lower part of said window having a vertical path of movement and the edge portion of the upper part of said window having a path of movement inclined to the vertical, said runway or channel comprising a generally channel-shaped structure having a base and a pair of side walls, said structure having its lower section thereof adapted to receive and support the vertically movable edge portion of the lower part of said window, and a pair of supplemental side wall members for the upper section of said structure, said supplemental side wall members being secured to the side walls of said upper section and being adapted to receive and support the other movable front edge portion of the top part of said window, said supplemental side wall members being provided at their lower ends with extensions secured to the side walls of the lower section of said structure and lying along the outer surfaces of said side walls between the inner and outer longitudinal edges thereof. 110
